Primary Examiner — W. A. Teddy Falloway

CLAIM

The ornamental design for a cubical ornament as shown and described.

DESCRIPTION

FIG. 1 is a top front right perspective view of the cubical ornament;

FIG. 2 is a bottom rear left perspective top view of the cubical ornament;

FIG. 3 is a front elevation view of the cubical ornament, where the left, right, and rear views all are mirror images;

FIG. 4 is a top plan view of the cubical ornament;

FIG. 5 is a bottom plan view of the cubical ornament;

FIG. 6 is a cross-sectional view along line 6-6 of FIG. 4 of the cubical ornament;

FIG. 7 is a top front right perspective view of an alternative embodiment of the cubical ornament;

FIG. 8 is a bottom rear left perspective top view of an alternative embodiment of the cubical ornament;

FIG. 9 is a front elevation view of an alternative embodiment of the cubical ornament, where the left, right, and rear views all are mirror images;

FIG. 10 is a top plan view of an alternative embodiment of the cubical ornament; and,

FIG. 11 is a bottom plan view of an alternative embodiment of the cubical ornament.

The broken lines appearing in the drawings are intended to illustrate portions of the cubical ornament and form no part of the claimed design.
